UNITED STATES PATENT OFFICE.

GEORGE F. MARCHANT, OF CHICAGO, ILLINOIS.

PEDAL.

SPECIFICATION forming part of Letters Patent No. 618,424, dated January 31, 1899.

Application filed October 18, 1897. Serial No. 655,603. (No model.)

To all whom it may concern:

Be it known that I, GEORGE F. MARCHANT, a citizen of the United States, residing at Chicago, in the county of Cook and State of Illinois, have invented a new and useful Improvement in Pedals, of which the following is a specification.

My invention relates to an improvement in pedals; and my object is to provide a pedal possessing extreme simplicity of parts, readily taken apart or put together, and having bearings which are practically dust-proof. Incidentally the cost of manufacturing the pedal is lessened materially, and the pedal is lightened in structure and enhanced in appearance.

I accomplish my purpose by making the pedal sleeve or barrel removable from the pedal-frame along with the pedal-crank pin, the ball-bearing being entirely within the sleeve and removable with it. Such an arrangement besides contributing to the dust-proof feature of the pedal also provides for the easy and nice adjustment of the ball-bearing. Other points of advantage will be suggested by the description which follows.

In the accompanying drawings, Figure 1 represents a development of the peripheral band or foot-bearing portion of the pedal-frame. Fig. 2 is a broken sectional view of the pedal and crank-pin; Figs. 3 and 4, views in elevation of the inner and outer cross-pieces, respectively, of the pedal-frame; Fig. 5, an inner end view, on a reduced scale, of the pedal barrel or sleeve; and Fig. 6, a longitudinal sectional view of the same.

A is a stamped band or frame-blank provided in the stamping operation with perforations $t' t'$ and $s' s'$, which serve as sockets for cross-pieces B and C. (Shown in Figs. 3 and 4, respectively.) The cross-pieces are provided at the ends with studs $r' r'$ and $q' q'$, respectively, which fit into the sockets mentioned after the frame-blank has been bent to shape, and by means of these studs the cross-pieces are riveted in place. The cross-piece B is provided centrally with an outwardly-turned ring or flange B', stamped integral with it and internally threaded, as shown, and the cross-piece C is provided centrally with an outwardly-extending cup-shaped depression C' of somewhat smaller diameter than the

ring B' and stamped integral with the cross-piece.

Fitting into the cross-pieces is a pedal sleeve 55 or barrel D, having its inner end (the end toward the wheel) provided with a head D', having wrench-engaging surfaces, as shown. The barrel D being comparatively short and therefore of comparatively small cost I prefer 60 to make it entirely of steel, providing it at the inner end with a hardened ball-bearing surface p and toward the outer end with an integrally-formed interior cone n . The sleeve D receives a crank-pin E, which is provided 65 at one end with a ball-bearing surface m and has its opposite end reduced in cross-section and provided with a thread l , said reduced portion being adapted to receive a threaded cone k , a washer k' , and a nut k'' . The outer 70 end of the barrel D may be made to fit so snugly into the cup C' as to exclude dust effectually, the bottom of the depression serving as a dust-excluding cap which protects and closes the outer end of the barrel. The 75 cavity which receives the outer end of the barrel may be characterized, therefore, as a bottomed depression as distinguished from an uncovered perforation. The only portion at all open to exposure is where the crank-pin 80 E contacts at the ring E' with which it is supplied with the enlarged end of the barrel, and this is in a position where it may be supplied readily with a dust-cap, though I have shown 85 none in the drawings.

The greatest advantages of my pedal lie, as I have pointed out, in the extreme simplicity of its parts, the readiness with which they may be assembled, and the easy and nice adjustment of the ball-bearing.

Suppose it is desired to clean or adjust the bearing. It is necessary only to place a wrench upon the head D' of the barrel D, when the latter can be readily separated from the pedal. This leaves the nut k'' exposed, and by means 95 of the fingers or of a wrench adapted to fit into the outer end of the barrel this nut can be removed, and after that the cone k can be removed or adjusted at will.

While I consider the construction shown 100 and described best adapted to my purpose, yet I do not wish to be understood as in any sense limiting myself to specific details, except as shall appear from the appended claims.

What I claim as new, and desire to secure by Letters Patent, is—

1. A velocipede-pedal comprising a frame having cross-pieces, a sleeve removably secured to said cross-pieces, a crank-pin removably and adjustably secured within the sleeve and ball-bearings between the sleeve and crank-pin, and independent of the frame, whereby the latter is detached without dismemberment and without disturbing the bearings, substantially as described.

2. A velocipede-pedal comprising a frame having an inner cross-piece provided with an integral bottomed depression, and an outer cross-piece provided with a threaded opening, a sleeve one end of which occupies the depression, and the other end of which is threaded to engage the opening, a crank-pin in the sleeve, ball-bearings between the sleeve and crank-pin and independent of the frame, and means for adjusting the bearings accessible

after the detachment of the frame, substantially as described.

3. The combination of a pedal-frame provided with pedal-sleeve supports, an integrally-formed readily-removable pedal-sleeve extending through the inner one of said supports with which it has screw connection and having its inner end enlarged and provided interiorly with a ball-bearing surface and its outer end provided with an interior ball-bearing surface, a crank-pin in said sleeve provided with a ball-bearing surface *m* and a reduced and threaded outer end portion, and a cone having screw connection with said reduced end portion, substantially as and for the purpose set forth.

GEORGE F. MARCHANT.
